UNITED STATES PATENT OFFICE

GAYLORD A. BARCLEY, OF SOUTH ORANGE, NEW JERSEY

CORSET AND SIMILAR GARMENT

Application filed December 8, 1925. Serial No. 74,109.

This invention relates to a corset or the like provided with an inner abdominal support connected at its opposite ends to the body of the garment by a vertical series of 5 adjusting straps for positioning the support so that it will properly support the wearer at different parts of itself vertically of the body. Heretofore, such straps have extended through slits at the front of the 10 garment to buckles upon the outside of said front, so that the buckles and free ends of the straps therebeyond were exposed and sometimes showed through the wearer's gown.

15 The objects of the present invention are to secure a construction by which the adjustable straps for the abdominal support and the buckles of said straps, are inside the garment, so as to be covered and concealed thereby, and yet said straps firmly supported and securely positioned to prevent any possible displacement of the support and readily accessible for the purposes of adjustment and of taking off and putting on the 25 garment; to provide novel and improved means for shifting the straps as a whole without disturbing their relations to each other; to secure a pleasing appearance in this type of garment, and great comfort, and to obtain 30 other advantages and results as may be brought out by the following description.

Referring to the accompanying drawings, in which like characters of reference indicate the same parts throughout the several 35 views,

Figure 1 is a view of a wearer putting on a corset brassière embodying my invention;

Figure 2 is a front view of the garment as it appears on the wearer;

Figure 3 is a cross-sectional view upon line 3—3, Fig. 2, and line 3—3, Fig. 4;

Figure 4 is a front view showing the body of the garment opened into a plane and divided at its back on a vertical central line to allow the divided parts to draw apart until the abdominal support is flattened out in a plane;

Figure 5 is a vertical section on line 5—5, 50 Fig. 4, looking in the direction indicated, il-

lustrating the adjustability of the straps as a whole upon their attaching flap;

Figure 6 is a perspective view of the attachment of one of the straps, the middle one, to said flap, and

Figure 7 is a detail sectional view of the same, taken longitudinally through the strap and being a portion of Fig. 3 on larger scale.

In said drawings, 1 indicates the body portion of a corset brassière adapted to encircle a wearer and having lacings 2, 2 at its sides under the arms and adjacent hook-and-eye connections 3, 3 just forward of said lacings. A pad or support 4 is provided for the abdomen of the wearer, at the inside of the body 1 of the garment, and straps are shown at the opposite ends of said support by which it can be adjusted and positioned. Three of these straps are shown at each end of the support, 5, 6 and 7 at one end and 8, 9 and 10 at the other end, see Figure 4, but any other number could be employed, if desired. Those at one end are just like those at the other end, except that at one end each of the straps, as 5, 6 and 7, is detachably secured to the support independently of the others, as will be more fully explained hereinafter.

The said straps of each set extend rearward at the side of the wearer, from the ends of the support 4, and pass through individual buckles 11, 12 and 13 so that the free ends 14, 15, 16 and 17, 18, 19 of the straps return forward toward the front of the wearer where they are convenient of access for adjustment. Continuations 20, 21 and 22 of the straps 8, 9 and 10 are shown extending across the front of the support 4 and secured thereto as by stitching, as is preferable but not essential, and the buckles 11, 12 and 13 are shown of the well-known kind having a biting edge 23 and sliding bar 24, see Figure 6, although any other suitable kind might be employed.

According to my invention the sets of buckles 11, 12 and 13 are arranged inside the body portion 1 of the garment so that they will be covered and concealed by said body portion, and I have shown this ac-

complished in the following manner. The buckles 11, 12 and 13 of each set are secured to the ends of tabs 25, 26 and 27 respectively, said tabs and buckles overlying the outside of a flap 28 the edge of which extends beneath a stiffener pocket 29 of the garment and is stitched therewith in place, as at 30. This secures a strong and secure attachment of the flap 28 to the inside of the body portion of the garment, and the tabs 25, 26 and 27 are stitched, as at 251, 261 and 271, to the inside of an attaching-piece 31 which is in turn stitched, as at 311, to the outside of the flap 28. By this arrangement, the tabs are properly and permanently located with respect to one another and yet they can be shifted as a whole up and down on the garment by ripping off the attaching-piece 31 and sewing it onto the flap again higher up or lower down. Although garments of this type are usually made to order upon measurements, it sometimes happens that a wearer wishes later to shift the support up or down, and my improved construction enables this to be done.

It will be noted that the stitchings 251, 261 and 271 extend only through the attaching piece 31 and adjusting fastenings or tabs 25, 26 and 27, while the stitching 311 which secures the attaching piece 31 to the flap 28 extends not only through said attaching piece and fastenings or tabs 25, 26 and 27 but also through the flap 28. When the attaching piece is ripped off, therefore, for adjustment up or down, only the stitching 311 which unites the adjusting fastenings or tabs 25, 26 and 27 with the flap, is severed, and the other stitchings 251, 261 and 271 of the fastenings or tabs 25, 26 and 27 to the attaching piece 31 are not disturbed.

With the attaching-piece in position, the garment is put on by a wearer as shown in Figure 1, and the support 4 adjusted by the manipulation of the several straps individually to exactly the position the wearer desires it, and then the body portion fastened in place to cover said support. Thereafter, in every-day wear, the straps at one end of the support are disengaged from the support and reengaged therewith by the detachable means previously referred to herein, the buckles being loosened to permit such disengagement and tightened again after reengagement. Said detachable means connect the straps at said end of the support to said support each independently of the others, as set forth in my copending application Serial No. 74,108, filed herewith, to which reference may be had for fuller description, if desired. Briefly, each of the straps 5, 6 and 7 is provided at its end next the support 4 with a member 32 adapted to separably engage a cooperating member 33 on the support, Figure 6, so that by disengaging said member for each strap in turn the support 4 is

released and the garment can be removed and put on again coat-wise. By my present improved adjusting means, wholly within the body portion of the garment, perfect adjustment of the support can be made with it fully exposed and open to view before the body portion is closed, and great comfort obtained. Then when said body portion is closed it covers the support and if properly adjusted by the lacings 2, 2 reinforces it, the outward appearance in no way disclosing the support.

While I have shown my improvements as applied to a corset brassière, this has been done for convenience only, and of course they can be employed with corsets and similar garments of any kind to which they are applicable. Also, various modifications may be made in manufacturing said improvements, without departing from the spirit and scope of the invention, and therefore I do not desire to be understood as limiting myself except as required by the following claims when construed in the light of the prior art.

Having thus described the invention, what I claim is:

1. The combination in a corset or similar garment having an inside abdominal support, of a flap at the inside of the garment secured at one edge thereto and having its opposite edge free and projecting toward said support, and adjusting fasteners for the support secured to said flap between it and the inside of the garment.

2. The combination in a corset or similar garment having an abdominal support, of a flap secured at one edge to the body of the garment and having its opposite edge free and projecting toward said support, an attaching-piece sewed upon the free portion of said flap at a distance from its secured edge, and adjusting fasteners for the support secured to said attaching-piece by means independent of the stitching securing the attaching piece to the flap, whereby said fasteners can without disturbing their relations to each other be shifted as a whole upon the flap by removing the attaching-piece and replacing it.

3. The combination in a corset or similar garment having an abdominal support, of a flap secured at one edge to the body of the garment and having its opposite edge free and projecting toward said support, adjusting fasteners for the support, an attaching piece secured by stitching to the outer ends of said fasteners, and other stitching independent of the first-mentioned stitching securing the attaching piece and fasteners to the flap whereby said fasteners can without disturbing their relations to each other be shifted as a whole upon the flap by removing the attaching piece and replacing it.

GAYLORD A. BARCLEY.
